United States Patent Office.

JOHN ROGERS, OF NEW YORK, N. Y.

Design No. 3,843, dated February 8, 1870.

DESIGN FOR A GROUP OF STATUARY.

The Schedule referred to in these Letters Patent and making part of the same

To all whom it may concern:

Be it known that I, JOHN ROGERS, of the city, county, and State of New York, have invented or produced a new and original Design for a Group of Statuary; and I do hereby declare that the following is a full and exact description of the same.

The group is called the "Parting Promise," and consists of two figures. A young man stands resting against a stone-wall, with his left foot on his valise, which lies on the ground. He is about to take leave of a young lady who stands on his left, with her right hand over his shoulder. Her other hand rests in his,

while he puts a ring on her finger, all of which is fully shown in the accompanying drawings.

Having thus described my invention,

What I claim and desire to secure by Letters Patent, is—

The design for a group of statuary, as herein shown and described.

JOHN ROGERS.
